UNITED STATES PATENT OFFICE.

NELSON B. HENRY, OF ATLANTA, GEORGIA, ASSIGNOR TO THE MURRAY COMPANY, OF DALLAS, TEXAS, A CORPORATION OF TEXAS.

COTTON CLEANER.

Application filed November 11, 1922. Serial No. 600,297.

To all whom it may concern:

Be it known that I, NELSON B. HENRY, a citizen of the United States, residing at Atlanta, in the county of Fulton and State of Georgia, have invented certain new and useful Improvements in Cotton Cleaners, of which the following is a specification.

My invention is a novel cotton cleaner and aerator particularly designed to operate upon low grade cotton that has been baled, especially linters.

Low grade lint cotton and linters, as received in bales at the mills usually carry considerable quantities of sand, dirt and trash, which owing to the compression to which the cotton mass has been subjected in the baling process has become very intimately embedded and entangled in and among the fibers of the cotton, so that its removal is difficult and commonly not thoroughly performed, the cotton itself being so compressed and compacted as to be matted and solid, the air having been largely expressed and evacuated from the cotton mass.

It is an object of my invention to thoroughly open aerate and clean such low grade cotton and to that end to give the maximum screening to it, possible in a machine of a given size; to open the cotton by the interaction of beater arms, screens and air currents and to thoroughly aerate the cotton by pneumatically carrying it through a suitably designed chamber in a cyclonic path, separating the fibers as much as may be by the cyclonic air currents whirling within the chamber in connection with the other elements.

In the drawings:

Figure 1 shows, in diagrammatic form, a typical installation of my cleaner-aerator;

Figure 2 is an elevation of the cleaner chamber mainly in longitudinal section.

Figure 3 is a cross-section on line 3—3 of Figure 2.

Figure 4 is a plan view of the chamber of Figure 2 the interior parts indicated in dotted lines.

Figure 5 is a cross-section on line 5—5 of Figure 4.

As indicated diagrammatically in Figure 1, the air current employed in my cotton cleaner-aerator is induced by a fan A, which sucks cotton through a pipe B, from the bale opener C to and through the cyclone

cleaner chamber and from the chamber by a pipe B' to the suction side of the fan, through which the cotton passes and is then discharged with the air blast through a pipe B² preferably to a condenser D, where the cotton fibers are separated from the air, forming a light bat on the condenser surfaces, ready for further operations in the mill. The bale opener, pneumatic pipes, fan and condenser are all well known instrumentalities in the art which require no explanation as to their mechanism, beyond the diagrammatic showing of the organization of these elements, made in Figure 1.

The gist of my new invention lies in the new cleaner and in the organization of the old elements with this new cleaner, to obtain the desired mode of operation and results.

The cleaner is made up of an air tight outer casing, 1, within which is a curved wire mesh surface 2, extending longitudinally thereof. In the central, longitudinal axis of the casing and curved screen is mounted for rotation a shaft 3 driven by a pulley 31 and carrying beater arms 4, the free ends 41 of which are set at an angle, tending to move the cotton in a spiral path from the inlet end to the outlet end of the cleaner. At one end of the cleaner, pipe B passes through the outer casing 1 and its open end is connected to a corresponding opening in the curved screen 2 (see Figs. 2, 3 and 5). The point of entry of pipe B is at one end of the casing, so directed that the air current moving into the casing through pipe B is tangential to the path of the beater arms 4 and in the same direction as the motion of the beater arms. The incoming air current moves in a spiral path within the casing, gradually circling to the exit end of the casing and during its course it carries a load of cotton which is at the same time thrown by the arms against the screen and back into the air stream, the ends, 41, of the arms 4, which are at an angle to the axis of the machine, aiding in urging the cotton around and lengthwise of the screens and chamber simultaneously.

It is to be observed that the air in pipe B, the cleaner and pipe B' is under tension, and the tension is practically uniform from end to end of the system, and the air stream, upon entering the cleaner does not spread as would be the case if the stream were under compression. This is advantageous as the

integrity of the stream is thus more nearly maintained and the load more evenly distributed, carried and sustained, for the better breaking up of mats into fibrous form, 5 the cotton, as it comes from the bale opener and enters the cleaner, being in units of aggregated fibers. The course of the air stream and cotton covers the screen from end 10 to end of the cleaner, whereas in other cleaners, in which the cotton entered at the top side of the casing, above the beater shaft and in a direction longitudinal of the cleaner and across the path of the beater arms and was directed to the exit at the other end, the 15 cotton was carried along the cleaner so that the screens at the bottom at the incoming end were not covered or utilized. Furthermore the beater arms moving across the path of the air current broke and destroyed it so 20 that its load was deposited on the screens and the process became purely a screening process, as distinct from the beating of air-sustained cotton and cleaning and aerating process above described, in which mats and 25 bats are beaten in air into their constituent fibers, as well as subjected to screen action when they fall upon the screens.

In previous cleaners, in which seed cotton was operated upon, in its path to the gins, 30 the suction was cut off from time to time and the air current ceased and this fact was taken advantage of to evacuate the dirt and trash from the cleaner; the dirt being pushed by a screw conveyer into a hanging canvas cylinder held closed at the bottom by atmospheric pressure so long as the suction was effective 35 in the cleaner but opening and dropping its contents when the suction was broken. In my new cleaner-aerator the suction is constant and continuous during operation and the old method of dirt evacuation is not available. I have shown in Figure 2 a continuously operating dirt ejector, consisting 40 of a screw conveyor 5 driven by belt 51 and pulleys 52 and 32 from shaft 3. The dirt falling through screen 2 is guided by the 45 converging sides of the casing 1 to the screw

conveyor (see Fig. 3) by which it is urged to the left in Fig. 2 and forced into a cylinder 53 and against a conical valve 54 which 50 closes the outer end of cylinder 53, the valve 54 being pressed to a seat by a spring 55. When cylinder 53 is filled with dirt further increments of dirt at the inner end force 55 open the valve 54 and the dirt is thereafter ejected at the outer end of the cylinder as fast as additional dirt is forced into the cylinder at its inner end by the screw 5. The plug of dirt contained in the cylinder during operations prevents the entrance of air. 60

I claim:

1. The cotton cleaner above described, made up of an air-tight casing; a screen chamber within the casing; beater arms mounted for rotation about the longitudinal 65 axis of the screen chamber and casing; an air and cotton inlet opening, at one end, through the casing side wall to the interior of the screen chamber, directed tangentially to the circular path of the beater arms and 70 in the direction of the rotation thereof; an air and cotton exit opening, at the other end from the interior of the screen chamber, through the casing side wall; a fan to create an air current through the tangential inlet 75 opening and through the screen chamber to the exit, substantially as shown and described.

2. The cotton cleaner above described, made up of an air-tight casing; a screen 80 chamber within the casing; beater arms mounted for rotation about the longitudinal axis of the screen chamber and casing; an air and cotton inlet opening, at one end, through the casing side wall to the interior 85 of the screen chamber, directed tangentially to the circular path of the beater arms and in the direction of rotation thereof; an air and cotton exit opening from the interior of the screen chamber, through the casing side 90 wall.

Signed at Atlanta, Georgia, this seventh day of November, 1922.

NELSON B. HENRY.
